UNITED STATES PATENT OFFICE.

SEBASTIANO MAGNANO, OF LAWRENCE, MASSACHUSETTS, ASSIGNOR TO MAGNANO CORPORATION, OF LAWRENCE, MASSACHUSETTS, A CORPORATION OF MASSACHUSETTS.

STRAND-MANIPULATING DEVICE.

Original application filed January 11, 1921, Serial No. 436,442. Divided and this application filed June 23, 1923. Serial No. 647,254.

This invention relates to strand separating mechanism and more particularly to means for successively picking off and separating the endmost strand of a sheet of strands, 5 such, for example, as the yarns of a weaving warp to facilitate the application of detached loom elements, including metallic drop wires, individual heddles, etc., thereto, the present application being a division of 10 my copending application, Serial No. 436,442, filed January 11, 1921.

When mechanisms of the character described are employed for placing detached elements in position for engagement with 15 silk warps, difficulty has been experienced due to breaking of the warps by the abrasive action of the separator means commonly employed for parting the last warp of the series for the placing of a warp engaging 20 element relatively thereto. Such separator has commonly been of flexible but relatively hard material such as spring steel, and as it frequently engages several warps before separating the last warp from the series it in 25 consequence may slip over the same warp more than once, thus weakening the warp sufficiently to cause it to break under subsequently applied strains. One object of the 30 present invention is to improve such separating means whereby to avoid such undesirable abrasive effect on the warp threads. One mode of attaining this object is to employ a relatively soft and resilient material as the engaging element of the separator device, the preferred arrangement comprising 35 a brush providing a resilient warp contacting surface such as a tuft of bristles sufficiently flexible to avoid undue strain upon the warp threads while at the same time 40 serving to separate the last warp from the series.

In order to permit the ready separation of the last warp thread by the separator device it has been proposed to employ lease rods for 45 dividing the warps into upper and lower sheets, the warps of one sheet being transferred in crossing relation to the warps of the other sheet at a point between the lease rods. With this arrangement it is desirable 50 to maintain the upper and lower sheets of warp a sufficient distance apart to prevent

any contact therebetween, but this requires the employment of lease rods of substantial diameter at a point closely adjacent to the location of the picking device. A further 55 object of the present invention is to provide means whereby the crossing of the warps may be accurately determined, such crossing always occurring in the vertical plane of movement of the separator device, while at 60 the same time providing for holding back the warps of the two series by the engagement therewith of the hold-back devices at points laterally removed from the point of separation. To this end lease rods of relatively 65 small diameter may be employed adjacent to the picking mechanism and other rods of larger diameter may be inserted between the warp sheets at points laterally removed from the first lease rods. 70

A preferred arrangement for carrying the above objects into effect is disclosed in the accompanying drawings, in which,—

Fig. 1 is a right side elevation of a machine embodying the present invention arranged in position for use, certain parts being broken away to show interior constructions; 75

Fig. 2 is a fragmentary elevation of the left side of the machine; 80

15

Main frame.

1, 2 are rail members which may be considered as constituting portions of the machine, such rail members being adapted temporarily to be supported upon a loom frame 20 transversely of the warp threads stretched therein and serving to support the operative portions of the machine as the latter is moved from one side of the loom frame to the other. The frame of the machine proper 25 comprises a pair of spaced side plates 3, 4. At the lower forward corners of the plates 3 and 4 are provided bosses 5, 6 in which are fixed stub shafts having mounted thereupon flanged truck wheels 7, 8 respectively, 30 such wheels being adapted to be supported upon the upper edges of the rails 1, 2. Passing through suitable openings in the rear lower corners of the members 3, 4 is a shaft 9, carrying a pair of flanged truck wheels 35 which also rest upon the rails 1, 2. The shaft 9 may if desired be extended to the right and have secured thereto a hand wheel 14 by the rotation of which the shaft, together with its wheels may be turned, thus 40 providing for the manual traverse of the frame, with the mechanism supported thereon, along the tracks. The right-hand frame member 4 is preferably provided with a rearwardly extending member 15 (Fig. 1) 45 which may be integral with the member 4 or fixed thereto in any desired manner. The member 15 extends downwardly as at 16 and forwardly as at 17, being connected at its forward extremity to the lower portion 50 of the frame member 4. For convenience of construction, the member 17 may, if desired, be made as an independent member secured at its ends to the member 4 and the member 16 respectively, the exact arrangement of 55 such parts however being unessential.

Adjacent the rear extremity of the member 17 is provided a stub shaft 18 carrying a flanged truck wheel 19 engageable with the rail 2 and serving to support the members 15, 16, 17 with their associated parts.

Near their upper extremities, the plates 3 and 4 may be provided with bosses 20, 21 (Fig. 3) having aligned openings therethrough for the reception of a main driving shaft 22, such shaft having collars 23, 24

fixed thereon and bearing upon the inner sides of the frame members, respectively. Fixedly secured upon the shaft 22 is a worm wheel 25 engaging which is a worm 26 mounted upon a shaft 27 which is preferably driven directly by an electric motor (not shown) suitably supported upon the frame or parts carried thereby. To the left of the frame member 3, as indicated in Fig. 3, is arranged a sleeve 28 fixed upon the shaft 22 and to the right of the frame member 4 a similar sleeve 29 is secured to the shaft 22. Integrally or otherwise secured to the sleeve 28 is a three-part crank and to the extremity of the sleeve 29 is secured a similar three-part crank, the respective cranks serving to drive mechanism to be hereinafter described. Fixed upon the shaft 22 or integral therewith at a point intermediate the sleeve 29 and frame 4 is a gear wheel 35 such gear wheel serving to actuate certain mechanism hereinafter referred to. The frame members 3, 4 are provided with vertical aligned slots respectively with which are adjustably engaged the lateral edges of a vertically sliding head or carrying plate 39, this plate serving as a support for the picker mechanism.

Magazine.

The magazine employed in connection with this machine is of quadruplex type, permitting the successive discharge of drop wires or similar elements from four independent series. For holding the drop wires in such independent series, the magazine comprises four substantially parallel bars supported at their rear ends and free at their forward ends where they terminate behind plate 39 at a distance from its rear surface substantially equal to the thickness of a drop wire. The bars are of a thickness such as to permit the suspension thereon of drop wires of the hair-pin type, the legs of such drop wires straddling over the bars.

In Fig. 1, 54 indicates a series of drop wires supported upon the magazine bar and for compacting and feeding forward the drop wires toward the forward extremities of the bars, each bar may be provided with a spring-pressed follower plate 55 arranged to engage the rearmost drop wire of the series carried by such bar. The member 16 has connected thereto or integral therewith an upwardly extending member having bearings therein for the rear ends of a pair of screw-threaded shafts 57, 58, the forward extremities of which are suitably supported in any suitable manner adjacent to the head 39. Such shafts have threaded engagement with screw-threaded openings in the upper and lower portions respectively of a sliding plate 59 arranged above the upper edges of the magazine bars. Passing freely through pairs of vertically spaced openings in the

plate 59 are rods such as 60, the rods of each of the respective pairs being fixedly secured to a corresponding plate 55. Compression springs 62 encircle the rods 60, being interposed between the member 59 and the several plates 55, the latter thus being resiliently urged away from plate 59. The rear ends of the shafts 57, 58 where they extend through the frame member 56 are connected by a suitable gear train to a transverse shaft 70 having bearings in the frame, said shaft extending to the right of the frame and having secured thereto a ratchet wheel 72. The shaft 70 is continued to the right of the ratchet wheel 72 (Fig. 1) and has pivotally supported thereon a pawl actuating lever 73. The shaft 70 also has secured to its outer extremity, to the right of the lever 73, a pinion 74 meshing with a gear wheel 75 journaled at 76 upon the frame member 16, said gear wheel 75 having a manually operable crank handle 78 by means of which it may be turned. 79 is a weighted pawl pivotally secured at 80 to the upper end of the lever 73 and having a tooth 81 for engagement with the teeth of the ratchet wheel 72. The lever 73 has a forwardly extending arm 82 to which is pivotally connected the rear extremity of a bar 83 extending toward the forward end of the machine where it is connected to a crank pin 84 carried by a crank 85 fast to a gear wheel 86. By the arrangement of parts thus described it will be evident that upon rotation of the wheel 86, the lever 73 will be oscillated, thereby causing the pawl 79 to turn the shaft 70 intermittently. The rotation of the shaft 70 through the gears above described, serves to rotate the screw shafts 57, 58, and thereby to feed the plate 59 slowly toward the forward end of the magazines. The plates 55, bearing against the rearmost drop wires of the respective series are thus forced forwardly, moving the wires 54 composing such series slowly towards the discharge ends of the several magazine bars. The springs 62 serve to compensate for any slight variations between the rate of forward feed and the rate of discharge, it being understood that the pitch of the screw threads 57 is calculated in accordance with the thickness of the drop wires for which the magazine is designed.

55 Pickers.

Cooperating with each of the magazines is a picker device for moving the foremost drop wire of the series in a direction substantially parallel to the length thereof, whereby to initiate its discharge from the magazine. These pickers consist of short bars or pins projecting rearwardly through vertical slots in the plate 39. The rear ends of these bars project beyond the rear surface 60 of plate 36 a distance substantially equal to

the thickness of a drop wire, and as the bars are vertically reciprocated in the slots they engage the upper ends of the foremost drop wires in the respective magazines and push such endmost wires downwardly.

70

A crank shaft 102 extends transversely between the frame members 3, 4 being journaled in suitable openings therein, such crank shaft being held in proper operative position by means of fixed collars thereon. 75 The crank shaft 102 is provided with four crank arms having crank pins arranged substantially 90° apart, and upon each of said crank pins is journaled the lower extremity of a connecting rod by means of which the respective picker bars or pins are reciprocated. The right-hand extremity of the shaft 102 extends to the right of the member 4 and has fixedly secured thereon the gear wheel 103, such gear wheel meshing with a gear wheel 104 fast upon a shaft 105 extending transversely through the frame members 3, 4 such shaft also having fixed thereon the gear wheel 86 hereinbefore referred to.

80

Secured in the frame member 4 are a pair of stub shafts 105a, 106 having mounted to turn thereon a pair of meshing gear wheels 107, 108 respectively, the wheel 107 meshing with the wheel 86 and the wheel 108 meshing with the wheel 85 upon the shaft 22. By the arrangement of parts above described, upon rotation of the shaft 22, the crank shaft 102 will be turned and thereby the several picker bars or pins will be caused to reciprocate in their respective guide slots. The several gears of the gear train including the gears 25 and 103 are of such relative diameters that the velocity ratio of the shafts 22 and 102 is as four to one. Thus upon each rotation of the shaft 22, one of the picker bars will be caused to complete a full downward and upward movement, the relative arrangement of the crank pins upon the shaft being such as to cause the several pickers to move downwardly in succession.

95

The stroke of the pickers may be of sufficient length fully to discharge the drop wires from the magazine, or may be merely sufficient to cause the drop wires to be projected to a predetermined distance below the lower edge of the plate 39, whereupon the further movement of the drop wire element may be continued by secondary means.

100

Such secondary means may comprise a shaft 111 extending transversely between the frame members 3 and 4 and journaled therein, such shaft having fixed thereon, at points corresponding to the several pickers, a series of feed rolls 112. The shaft 111 is extended to the right of the frame member 4 and has fixed thereon, a pinion 114. This pinion meshes with the gear wheel 103 whereby the shaft 111 is driven. A second shaft is arranged parallel to shaft 111 and carries feed rolls which cooperate with the rolls 112.

110

115

120

125

130

The feed rolls as thus arranged constitute means for feeding onward the drop wires as they are pushed downwardly from the magazine by the reciprocating pickers.

5 124 and 125 are a pair of downwardly extended brackets fixedly supported at their upper ends on the shaft 44. 126 is a transversely extended bar having rearwardly extended ears whereby it may be attached to 10 the lower ends of the respective brackets 124 and 125. The lower part of the forward face of the bar 126 is provided with projecting lugs defining spaced channels 137 for the descending drop wires, the inner 15 faces of said channels having wedge elements engageable with one leg of a descending drop wire to force it forwardly out of its normal plane.

Secured to the lower portion of the bar 20 126 are a series of downwardly directed brackets having secured thereto forwardly extended supporting bars 147. The bars 147 may, if desired, be of circular cross section, although preferably they are flattened 25 laterally and of rectangular cross section, the lateral dimensions thereof, in any case being such as to permit them readily to pass between the legs of a drop wire which may be supported thereon. The several bars 147 30 are so arranged and spaced relatively one to the other as to occupy positions directly below the slots in the drop wires as they are fed downwardly from the respective series in the magazine, the bars 147 for this purpose being located substantially mid-way 35 between adjacent lugs of the bar 126.

As the drop wires are discharged from the magazine and fed downwardly they are caused to straddle over the corresponding 40 bars 147 and come to rest with the central webs 148 of the drop wires in contact with the upper surface of said bar. The drop wires as they are discharged from the magazine and placed over the warp threads are 45 not hung directly upon the latter but upon the bars 147 which thus receive the thrust of the drop wires imparted by the feed rolls and insure the warp threads against being subjected to a breaking strain. One or more 50 of the bars 147 may, if desired, be provided with rearwardly extended, curved horns 149, said horns riding over the warp threads supported in the loom frame so that all of 55 the threads of the warp sheet are caused to pass downwardly below the bars 147 into a single plane. When in this position the placing of the drop wires upon the warp threads is much facilitated.

When the bars 147 are provided with flat 60 lateral faces, said faces serve, in cooperation with the warp threads, to oppose any lateral tipping of the drop wires as they are deposited upon the threads, and thus any intermingling of the drop wires of the several 65 parallel banks or series is avoided. By the

time the drop wires reach the forward ends of the bars 147, a sufficient number of the same have been placed in contact to provide the necessary friction to avoid tipping while the gradual movement of a drop wire down 70 the inclined front end of the bar prevents any severe shock to the warp when the weight of the wire is finally imposed thereon.

Lease rods.

75 150 is a bracket which may be supported upon the rail 1, or upon the loom frame, this bracket extending to the left of the rail as viewed in Fig. 3. Additional brackets similar to bracket 150 but not shown herein, 80 will be provided at suitable points in the length of the rail 1 or loom frame, such brackets serving to support the large lease rods 151 and 152 and also the small lease rods 153 and 154. The lease rods 151 and 152 are of proper diameter to maintain the planes of the upper and lower series of warps at a sufficient distance apart to permit operation of the hold-backs hereinafter to be described. The small lease rods 153 and 154 are of the diameter which permits them to be placed closely together without 85 subjecting the warps to undue strain. The crossing of the warps of the two series takes place between such small lease rods. 90 95

Warp separating.

On the shaft 111 is fixed a gear 155, (Fig. 1), said gear meshing with an idler gear 156 carried upon a stub shaft secured to 100 the frame member 4. Engaging with the idler gear 156 is the gear 157 mounted upon the right hand end of a shaft 158 which extends transversely across the frame, and to the left of the frame member 3, as indicated 105 in Fig. 3. Fixed to the left hand extremity of shaft 158 is a bracket 159 (Fig. 12) carrying a substantially flat plate 160. Cooperating with plate 160 is a second plate 161 which may be adjustably secured to the plate 160 by means of screws 162 or in any suitable and desirable manner. Between members 160 and 161, which, together with screws 162 constitute a clamp, may be secured a member 163 of steel to other suitable material having its lower end formed as a thin flexible selector blade 164 arranged to engage warp threads adjacent to the crossing point of the leased warps, whereby to separate said warps one by one. The parts are so arranged that as shaft 158 rotates, 110 blade 164 will be caused to rotate in the plane of the crossing of the leased warps and in a counterclockwise direction as viewed in Fig. 2. 115

The shaft 105, upon which gear 86 is mounted, extends transversely across the frame, and at the left of frame member 3 has fixed upon a pair of cams 165, 166. These cams are of complementary form hav- 120 125 130

ing active faces 167 and interposed dwells. A stub shaft 169 extends to the left from frame member 3 and has mounted thereon a pair of rock arms 170, 171 respectively, 5 said arms being provided at points intermediate of their lengths with rolls arranged to engage the surfaces of the cams 165 and 166 respectively.

A fixed shaft 174 extends to the left from 10 the frame member 3, and mounted to rock on shaft 174 are a pair of brackets 175, and 176 (Fig. 2). The brackets 175 and 176 are extended above shaft 174 upon which they are pivoted, and secured to the bracket 175 is a 15 rod 177 extending to the right toward frame member 3. At its right hand extremity rod 177 has fixed thereto a crank arm 178 to the lower end of which is connected the rear end of a connecting rod 179 whose forward 20 end is pivoted to the lower end of the arm 171. The bracket 176 is likewise provided with a rod 180 extending to the right, and to which is secured the upper end of a crank arm 181 connected by means of a connecting rod 182 with the lower end of the rocker arm 170.

Fixed upon the shaft 174 are collars such as 183, having ears 184 to which are connected the lower ends of springs 185 and 30 186, said springs being connected respectively at their upper extremities to ears 187 and 188 extending from collars carried upon the bars 177 and 180. By the arrangement herein described, upon rotation of shaft 105, 35 movement of oscillation will be imparted to the bracket 175 and 176 and associated parts, such movements taking place in alternation and the parts being so relatively arranged that the long circular dwell of one cam acts 40 to hold one of said brackets stationary during substantially the full movement of the other bracket in swinging toward or from such position, and vice versa. The springs 185 and 186 serve at all times to keep rolls 45 172 and 173 in engagement with their respective cams.

Secured in the lower ends of the respective brackets 175 and 176 are hold-back bars on arms 191 and 192. The arm 191 is substantially straight from its end to its bracket, while arm 192 is of irregular form as shown in Fig. 2 to prevent interference with the shaft 158. The lower portions of the hold-back arms are substantially straight 55 and are provided with warp engaging recesses 193 and 194, such recesses being of vertically elongated form, thus serving to provide against escape of the warp threads below the ends of the arms. The hold-back 60 arms or bars as described are so located relatively to the crossing point of the leased warps that the bar 191 is to the left of the lease crossing (see Figs. 4 and 5) while bar 192 lies to the right of the lease crossing. 65 These bars furthermore are of such a length

as to permit them to contact only with those threads of the warp lying in the upper plane, the position of the lower end of bar 191 being shown in Fig. 5.

As heretofore described, shaft 22 carries 70 at its opposite ends triple cranks 30 and 31 respectively. To the crank pins upon opposite sides of the machine are pivotally secured connecting rods 195, 196, 197; 198, 199, 200. A bracket 201 extends to the left 75 of frame member 3 and is secured thereto, and 202 is a bracket extending to the right of frame member 4. The brackets 201 and 202 serve to support series of vertically extending sleeves wherein are arranged for 80 vertical movement a series of rods 209, 210, 211; 212, 213, 214, which are pivotally secured to the lower ends of the respective connecting rods just described.

To the lower portions of the rods 209, 214, 85 (Figs. 1 and 6) are connected brackets 215, 216, respectively, serving to support downwardly directed bars 217, 218 said bars being beveled at their lower ends to form downwardly directed chisel edges. These 90 bars are herein designated as warp retainer members.

To the lower ends of rods 210, 213 are connected brackets 219, 220 respectively. Ex- 95 tending downwardly from said brackets (Figs. 1 and 6) are spaced members 221, 222; 223, 224, respectively. Members 221 and 223 are provided with rearwardly and downwardly curved faces such members converging toward and uniting with the members 222 and 224 respectively, at edges 225 and 226, from which edges the cam surfaces of members 222 and 224 curve upward and forwardly. 100

To the lower portions of the rods 211, 212 are connected brackets 227 and 228. These 105 brackets support pairs of downwardly directed rods 229, 230, 231, 232, respectively, said rods being spaced apart throughout their upper portions a distance approximately equal to the diameter of the warp threads. At their lower portions the pairs of members 229, 230; 231, 232 diverge to form V shaped guiding openings to receive and direct the warp threads into the space between said members 229, 230; 231, 232, respectively. 110

Downwardly directed bars 235 and 236 are also carried by the brackets 227 and 228, such bars at their lower ends curving downwardly and to the rear and uniting with the lower portions of bars 230 and 232 to form sharp edges 237 and 238. The bracket members 219 and 220 with the parts 120 supported thereby are hereinafter referred to as warp pusher members, while brackets 227 and 228 with their associated parts may be termed warp positioner members. 125

The operation of the parts just described 130

will be clear by reference to Figs. 6 and 9 inclusive, it being noted that the arrangement of the parts is substantially alike and the operation thereof simultaneous, at the opposite sides of the machine. It is sufficient however, to provide warp lease bars at one side only of the machine and to have cooperating therewith a single warp separator member 164.

10 Referring to Fig. 6 a series of unloaded warp threads is indicated A, B, A¹, B¹, A², B², etc. alternate threads lying in the upper plane of the leased warps at opposite sides of the crossing point, the last warp of the 15 A-group being indicated as lying between members 229 and 230 of the warp positioner.

The operation of the warp separating mechanism may be understood from inspection of Figs. 6 to 9 inclusive. In Fig. 6 the 20 hold-back finger 191 is shown in position to prevent escape of the forward warp A' of the warps forming the upper series at the left of the crossing point. The positioner 25 C is shown as holding a warp A which has been separated from the upper series of warps at the left of the crossing point, such warp being held thereby in proper relation to the descending drop wire to permit the 30 placing of the latter thereover. The warp hold-back finger 192 is shown in forward, inoperative, position; the warp pusher comprising members 221, 222 is in uppermost position, and the warp retainer comprising 35 the element 217 is moving upwardly and is near the upper end of its stroke. As seen in this figure the separator blade 164 is moving downwardly in the direction of the arrow.

In Fig. 7 the separator blade 164 has 40 moved downwardly into position to sweep over the series of warps immediately to the rear of the hold back finger 191, it being remembered that such separator blade contacts with the warps substantially in the vertical 45 plane of the crossing of the leased warps and may thus wipe off the end warp thread B of the series lying in the upper plane to the right of the crossing point and which is not restrained by the hold-back finger 191 or by 50 any other thread of the series. The retainer has risen to its uppermost point, the positioner is rising and is nearing the upper end of its stroke, and the pusher member is moving downwardly and has engaged the thread 55 A over which the drop wire has been hung, by means of its curved cam surface 222, and is about to push said thread laterally and to the right as seen in Fig. 7.

Between the position of Figs. 8 and 9 it is 60 assumed that the separator finger has made one and a quarter turns, the operation having proceeded to a point where threads A and B with their suspended drop wires have been moved forwardly and are re-

strained against back ward movement by 65 the retainer 217. In Fig. 8 the hold-back finger 191 has swung into operative position, the hold-back finger 192 has swung into operative position for restraining the leading 70 warp B' of the series of warps in the upper plane at the right of the crossing point and the warp thread A' has been left by the separator blade where it may be engaged by the positioner upon the next descent of the latter. The pusher has descended to its 75 lowest point carrying the threads A and B into the loaded series and the retainer has moved downwardly into position to retain said threads A and B against rearward movement upon the recession of the pusher member. The separator blade is shown as having passed out of engagement with the warp threads and is moving upwardly to 80 complete its revolution.

In Fig. 9 the retainer member has moved 85 to its lowermost position. The hold-back finger 191 has started to release the foremost warp B¹ of the upper series to the right of the crossing point, so that such 90 warp may be picked off by the separator member when the latter reaches the plane of the warps, while the hold-back finger 192 is just assuming its position ready to hold back the foremost warp A² of the upper 95 series to the left of the crossing point. The thread A' is positively held against lateral movement by engagement in the slot between members 229, 230 and is ready for the discharge of a drop wire thereon. These operations are repeated successively, whereby 100 warps are picked off alternately from the upper and lower planes of the leased warps, held by the positioner while a drop wire is placed thereon, pushed over into the loaded series 105 by the pusher element and retained against rearward movement by the retainer member. The general arrangement of the several 110 parts is shown in plan in Fig. 11.

Stop mechanism.

For stopping the machine automatically upon the breakage or absence of a warp thread, a stop mechanism such as herein-after described may be employed. As above noted the machine is preferably driven by an 115 electric motor mounted directly upon the machine frame or upon a part carried thereby. An insulating plate 240 is secured upon the bars 15, 17 of the machine frame in any desired manner, such plate having mounted thereon a magnetic circuit breaker of any desired form. This circuit breaker is herein shown diagrammatically (Fig. 19) as comprising electromagnets 241, 242 having 120 wires 243, 244 leading therefrom. 245 is an armature lever carrying an armature operable by the magnets 241, 242, such lever serving to make and break a circuit comprising 125

the wires 246, 247 such wires being included in the circuit through which the motor is driven.

One of the wires as 244 from the magnets may extend to one of the poles of a battery or other source of electrical energy, the opposite pole of such battery being grounded on the machine frame as at 244^a. The other terminal 243 is connected by means of a suitable conductor 249 with a plate 250, carried by an insulating bracket 251 secured to the machine frame in any suitable manner. The plate 250 is provided with a lower member 252 extending at right angles to the main portion thereof, and in a substantially horizontal plane. This portion of the plate may if desired be somewhat concave on its upper surface, this, however, not being essential.

The warp retainer heretofore described, comprising the bracket 215 and the rod 217, which is located at that side of the machine upon which the bracket 251 is mounted, has fixed thereon a pair of downwardly extending guide rods 253, 254 (see Figs. 16 and 17), said rods being substantially parallel and serving to guide a feeler plate 255 which is vertically slideable thereon. Connected to the central portion of the feeler plate 255 is a rod 256 of small diameter which extends upwardly through a suitable guide opening in the bracket 215 and at a point 257 is bent at substantially right angles to lie in a horizontal plane, the outer end of the horizontal extending portion 258 overlying the horizontal element 252 of the contact plate 250.

Referring to Fig. 17 it will be seen that the bracket 215, as the retainer member is lifted, lifts and supports the feeler member 255 by engagement with the member 258.

In Fig. 17, W indicates the position of a warp thread arranged to receive a drop wire thereon, this being the position in which the thread is held by the slot in the positioner. Downward movement of the retainer permits the feeler bar 255 to rest upon the warp

W if the latter is properly positioned, and thus as the retainer continues to descend the part 258 is supported above the upper surface of the contact member 252, thereby avoiding contact between the latter two members. If, while so supported, the warp thread W should break during the placing of the drop wire thereon or if, upon the descent of the retainer, the member 255 should encounter no warp thread, such member will continue to descend with the bracket 215 until the part 258 rests upon the contact member 252. Electrical contact will then be established through the conductor 249 and the frame of the machine whereby the magnets 241, 242 will be energized, thereby breaking the circuit including the motor windings, causing the motor to stop and bringing the machine to rest.

Under some circumstances it is found de-

sirable to provide the retainer bracket 215 with a second downwardly extending rod 259 having the guide rods 253, 254 disposed between said latter rod and the rod 217. The rod 259 serves particularly in abrupt stopping of the machine, to prevent improper displacement of the warps of the leased series and to assist the hold-backs in retaining such warps and preventing tangling of the same.

While the resilient metallic plate 164 is in most instances desirable as a means for separating the warps, it is found under some circumstances, particularly with very delicate silk warps, that such a metallic separator plate tends to abrade the warps in being dragged over the same. As an alternative and preferred form of a separator device, that shown in Figs. 14 and 15 may be employed. In such figures, a holder 260 may be clamped between the plates 161 and 160, said holder being twisted as indicated at 261 whereby its lower end lies in a plane substantially perpendicular to the plates 161 and 160. Secured in the lower end of the holder are a series of brush tufts or bristles 262. Such bristles may be of hair, fiber, or of fine wire as desired and are preferably beveled off as indicated at 263. As the member 159 sweeps around in the direction of the arrow, see Fig. 14, the brush bristles are caused to contact with the warps and to separate the last warp of the series by a very delicate contact therewith, the beveled edge of the brush providing against unnecessary contact of the bristles with the warps which are restrained against movement by the hold-back device.

While the arrangement shown in the drawings is a preferred form of the invention it is to be understood that various changes and modifications therein all within the skill of the mechanic may be made without departing from the spirit of the invention.

I claim:

1. In a device of the class described, means for supporting a sheet of strands, and a rotating brush for successively picking off strands from the edge of the sheet, said brush comprising bristles which move in a plane intersecting the strands.

2. In a machine of the class described, means for supporting a sheet of strands, a rotary shaft substantially parallel to the individual strands of the sheet, an arm secured to the shaft, a bristle brush secured to the arm, and means for rotating the shaft continuously in the same direction whereby periodically to wipe the brush across strands of the sheet.

3. In a machine of the class described, a rotating strand separator device comprising a holder having a series of brush bristles projecting from its extremity, certain of said

bristles being substantially longer than the others, the bristles rotating in a plane substantially perpendicular to the strands to be separated.

5 4. A machine of the class described having a thread separator comprising a holder having a flattened extremity and a series of bristles secured in said extremity and projecting therefrom, the bristles at one end of 10 said series being longer than those of the other.

5. In a machine of the class described, a separator device comprising a rotatable support, clamping means carried by said support, and a flexible thread engaging element 15 secured in said clamping means.

6. In a machine of the class described, a rotatable support, clamping means carried by the support, a holder secured in the 20 clamping means, and a resiliently flexible strand separating element carried by the holder.

7. In a machine of the class described, a rotatable support provided with a clamping 25 plate, a second clamping plate cooperable with the first plate, and a holder clamped between said plates, said holder being provided with a plurality of flexible strand separating elements.

30 8. In combination with a movable strand separating device, leasing means disposed closely adjacent to and upon opposite sides of the plane of movement of the separating device for dividing strands to be separated 35 into two series crossing substantially in the plane of movement of the separating device, and means for causing said series to diverge from each other upon remote sides of the leasing means.

40 9. In combination with a movable strand separating device and strand retaining elements, leasing means disposed closely adjacent to and upon opposite sides of the plane of movement of the separating device, said 45 leasing means dividing strands to be separated into two crossing series, and means for holding said series in widely separated planes in the vicinity of the retaining elements.

50 10. In combination in an apparatus of the class described, warp separating means, and means for supporting a series of warps in position for separation, said last means comprising a pair of lease rods of relatively

small diameter and a rod of relatively large 55 diameter lying substantially in the plane of said lease rods and spaced laterally therefrom, means for moving the warp separating means in a plane perpendicular to the warps and intermediate the lease rods of small diameter, and warp engaging means disposed between the large rod and the adjacent small rod.

5 11. In a machine of the class described, movable warp separating means, and means 60 for supporting a plurality of warps in position to be acted upon by said first means, said supporting means comprising a pair of lease rods for holding the warps in spaced intercrossing series, the separating means 65 moving in a plane substantially midway between said rods, a rod of a diameter relatively larger than said lease rods and substantially parallel thereto, said rod being positioned between said series of warps, and warp engaging means disposed between said 70 larger rod and the adjacent small rod and engageable with the warps of one series only.

12. In combination, in an apparatus of the 75 class described and a hold-back device, a strand separating device, and means for supporting a series of strands in position for separation, said means comprising a pair of lease rods of relatively small diameter 80 disposed adjacent to and upon opposite sides of the separating device, and a pair of lease rods of larger diameter spaced outwardly from the respective rods of small diameter, the hold-back device being between one of the small lease rods and the adjacent large 85 lease rod.

13. In combination with a strand separating device and strand retaining elements movable in substantially parallel planes, a pair of lease rods of relatively small diameter 90 disposed closely adjacent to and upon either side respectively of the plane of movement of the separating element whereby to divide strands to be separated into two series 95 crossing substantially in the plane of movement of the separator device, and a pair of lease rods of larger diameter for widely separating the two series of strands at the planes of movement of the respective retaining elements.

Signed by me at Lawrence, Massachusetts, this fifteenth day of June, 1923.

SEBASTIANO MAGNANO.

CERTIFICATE OF CORRECTION.

Patent No. 1,650,287.

Granted November 22, 1927, to

SEBASTIANO MAGNANO.

It is hereby certified that error appears in the printed specification of the above numbered patent requiring correction as follows: Page 8, line 80, claim 12, after the word "described" insert the comma and words ", a strand separating device", and lines 80 and 81, strike out the words and comma "a strand separating device, "; and that the said Letters Patent should be read with these corrections therein that the same may conform to the record of the case in the Patent Office.

Signed and sealed this 27th day of December, A. D. 1927.

Seal.
